[57] CLAIM

The ornamental design for a reagent tray, as shown and described.

DESCRIPTION

FIG. 1 is a perspective view of a reagent tray showing my new design, with cover on;

FIG. 2 is a side elevational view thereto with cover removed, the opposite side elevational view being a mirror image thereof;

FIG. 3 is a front elevational view, the opposite side elevational view being a mirror image thereof;

FIG. 4 is a top plan view thereof;

FIG. 5 is a bottom plan view thereof; and,

FIG. 6 is a cross sectional view taken along the line 6—6, the reagent container shown in broken line is for illustrative purposes only and form no part of the claimed design.

FIG. 1**FIG. 2****FIG. 3**6 ← FIG. 4

6 ← FIG. 5

FIG. 6
